UNITED STATES PATENT OFFICE.

WILLIAM W. WHITTON, OF OAKLAND, CALIFORNIA.

FURNACE.

1,222,251.

Specification of Letters Patent. Patented Apr. 10, 1917.

Application filed June 21, 1916. Serial No. 104,876.

To all whom it may concern:

Be it known that I, WILLIAM W. WHITTON, a citizen of the United States, residing at Oakland, in the county of Alameda and 5 State of California, have invented new and useful Improvements in Furnaces, of which the following is a specification.

This invention relates to an ore roasting furnace and fume condenser.

10 One of the objects of the present invention is to provide a simple, substantial, cheaply manufactured furnace and condenser which is particularly adapted for roasting ores or substances containing volatile metals such as quicksilver, zinc, etc., and which is so constructed that continuous operation, and practically perfect extraction, may be obtained without the employment of skilled furnace men or operators and without 15 subjecting the men to the danger of becoming salivated. Another object of the invention is to provide a roasting furnace in which variation of the furnace temperatures will have little or no effect as far as 20 extraction is concerned and in which losses by absorption are entirely eliminated.

The invention further consists of the parts and the construction and combination of parts as hereinafter more fully described and claimed, having reference to the 25 accompanying drawings in which—

Figure 1 is a central, vertical, longitudinal section through the furnace.

Fig. 2 is a plan section on line 2—2, Fig. 1.

30 Fig. 3 is a perspective view of one of the retort inclosing plates.

Fig. 4 is an enlarged central vertical section of one of the retort tubes.

Referring to the drawings in detail, A indicates in general a furnace constructed of 35 brick and suitably lined to resist high temperatures; 2 the fire-box and 3 a main heating chamber which is provided for the reception of a plurality of retort tubes generally indicated at B.

Extending across the main chamber 3 are a plurality of superposed frames 4, which are provided for the purpose of uniformly 40 distributing the heat from the fire-box about the retort tubes before escaping through the flue indicated at 5, which may be connected with a stack not here shown. Each frame 4 consists of an iron grating, see Fig. 2, provided with a plurality of staggered rectangular shaped openings. These openings 45 are provided for the purpose of permitting

the insertion of the individual retort tubes and also to permit the same to be readily removed when they are to be renewed or for other purposes.

60 Referring to Fig. 3, it will be seen that a retort inclosing plate is provided with lugs 6 which are so positioned as to engage the inner sides of the rectangular openings formed in the grate bar or frame 4, the position of the plates being shown in Fig. 2. Two plates are required for each retort tube and these plates, when placed in position about the tubes, form a perfect covering for each grate bar or frame 4 and thus prevent the hot furnace gases from escaping up through the grate bars around the tubes. The furnace gases coming from the fire-box will thus travel in the direction indicated by arrow a, through the staggered tubes, 70 then up through an end-flue 7, which communicates with a horizontal passage or flue 8 formed between the frames 4 and 4^a. The gases, after passing through this passage are deflected in an upward direction 75 through an end flue 9 and are finally permitted to escape through an upper flue 10 and the communicating discharge flue 5 before they are permitted to escape to the stack. The staggered position of the several retort tubes furthermore distributes the 80 furnace gases and this arrangement, together with the position of the several flues shown, permits an even and uniform heating of the tubes. Forming a closure for the 85 upper end of the main chamber 3 is a pair of frames 11 and 12. These frames may be constructed similar to the frames 4 or as here shown, and are preferably separated a sufficient distance to permit the formation 90 of an air chamber 13 to prevent escape or radiation of heat through the upper end of the furnace. Each individual retort tube is provided with a collar 14 at its upper end and these collars in turn provide means for supporting the individual tubes against endwise movement through the frames 11 and 12 and the frames 4 and 4^a. In other words, 95 it will be seen that each individual tube is hung or suspended from the upper frame 12 by means of the collars 14 and that their vertical position is maintained by means of the frames and the inclosing plates 6. Formed on each collar are two or more 100 upwardly projecting arms 15 and a perforated hub member 16. Extending through each hub member and the aligned retort tube

is a pipe 17. Each pipe is centrally positioned with relation to the retort tube through which it passes and is sufficiently long to extend a considerable distance above and below the individual retort tubes. Each pipe 17 is capped as at 18 at the upper end and each pipe 17 is perforated as at 19 along its entire length for purposes hereinafter to be described. Forming a bottom for the main chamber 3 is a frame 20. This frame is preferably constructed in a manner similar to that described in connection with the frames 4 and is also provided with removable plates 6 to prevent admission of air at this point. Mounted below the bottom frame 20 is a plate 21 and mounted below said plate is an inclosed tank 22, which is partly filled with water. The lower ends of the individual pipes 17 are connected with the upper end of this tank and the tank is in turn connected through a pipe 23 with a suitable form of condenser 50 and a suction blower 51. Mounted on top of the furnace A is an ore-bin 24, the bottom of which is formed by the frame 12 and the open ended retort tubes B. The ore delivered to the bin 24 is permitted to fill the individual retort tubes and the ore thus delivered to the individual tubes is prevented from freely discharging through the lower ends by the provision of the plate 21. This plate is positioned just below the open lower ends of the retort tubes and in this manner prevents the ore from freely discharging through the tubes.

In operation with a suitable fire maintained in the fire-box 2 and with the individual retort tubes charged with ore, it will be seen that the hot furnace gases will travel in the direction indicated by the arrows through the main chamber 3 with connected flues before they are permitted to escape through the discharge flue 5. The several tubes are thus uniformly heated from the bottom to the top and in actual practice an approximate cherry-red heat is maintained. The ore contents of the retort tubes are thus heated to an ideal temperature and the volatile minerals contained therein are freed and permitted to escape through the perforations 19 formed in the central pipe 17, this being caused by the suction produced by the condenser and blower which communicates with the individual pipes 17 through pipe 23 and tank 22. The liberated volatile products are thus drawn directly into the tank 22, where they strike the surface of the water contained therein. A comparatively large proportion of the products are here condensed and permitted to settle in the form of a pure metal while the remaining products are drawn through the pipe 23 where they are finally precipitated in the condenser. By drawing off the mercury or other gases distilled from the ore, it will be seen that a

comparatively small volume of gas is handled. It is therefore possible to use a small and simple form of condensing unit, something not possible when comparing the device with the shaft furnaces now in common use. In the operation of most forms of stack furnaces, it must be taken into consideration that the volatile contents of the ore are distilled by the heat obtained from the furnace gases, and that the liberated gases are mixed with the furnace gases. There thus results a very large volume of heated gas, all of which must be reduced to a low temperature to allow the liberated volatile metals to condense. It has been found by practical experience, that these furnace gases must be cooled to a temperature, particularly where Cinnabar ores are treated, below the boiling point of mercury and also that it is practically impossible to catch more than ninety per cent. of the mercury in the ore in the best type of condensers, and as the furnaces are commonly operated, only about seventy-five per cent. of the mercury is caught in the condenser. One reason for the difficulty in condensing the mercury is the extreme dilution of the gases as regards mercury. This permits particles of mercury of molecular fineness, to be carried through the condenser, even by the most gentle air current. A second reason for the difficulty in securing condensation of the mercury is the nature of the gases from which it is to be condensed. The furnace gases not only contain the ordinary products of combustion from wood and oil fuel but also the volatile products of the ore. Cinnabar, the sulfid of mercury from which quicksilver is obtained, sets free sulfur when it is reduced to metallic mercury. It also happens that the majority of Cinnabar ores, almost without an exception, contain sulfid of iron and other metals, which sulfids set free sulfur which is oxidized by the oxygen of the air, thus producing sulfurous or sulfuric acid, both of which are very corrosive. It is therefore necessary to construct condensing apparatus of the flue-cooling type, such as are ordinarily used in connection with shaft furnaces of material that will withstand the action of these acids and the only material that has been found to successfully withstand this action for any reasonable length of time is brick. While brick is ordinarily used as a heat insulating material, it is here used in the construction of chambers which are supposed to reduce the heat of the gases passing through them. It follows therefore, that these condensing chambers as used in connection with the ordinary shaft furnaces, are of enormous size and expensive construction.

The amount of air admitted to a furnace of the shaft type and which passes through condensers, such as described, is governed

by the needs of the fuel employed, rather than by the more proper need of carrying off the mercury and other volatile constituents of the ore. It therefore follows that 5 the furnace on the shaft type with connected condensers, requires the attention of expert and experienced furnace men and operators to produce anything approaching a high extraction.

10 With a furnace constructed as shown in the present instance, the products of combustion are not brought into direct contact with the ore nor is the ore raised to a temperature which will liberate the injurious 15 gases having the corrosive nature, as previously described. By drawing off the mercury or other gases distilled from the ore, a comparatively small amount of gas to be condensed is produced and it is furthermore 20 possible, to regulate the amount of gases so drawn into the condensers independently of the needs of the fire. The small amount of corrosive gases produced are immediately drawn out and brought into contact with 25 the water contained in the tank 22. The corrosive substances are thus immediately removed and the life and general efficiency of the furnace increased. The amount of heat used in my furnace is governed en- 30 tirely by the need of raising the ore in the retort tubes to the proper temperature. This temperature in actual practice is approximately a dull red and the condition of the tubes may be observed at all times 35 through doors formed in the ends or at other convenient points around the furnace. Any fluctuation in the furnace temperature will therefore have little or no effect as far as the extraction is concerned. The ore set- 40 tling through the tubes from the bin 24 may be continuously removed from the lower ends by the use of a rake or a slice bar passed over the plate 21. The treated ore is in this manner discharged on either 45 side of the furnace and may be removed in cars or otherwise disposed. Secured on the lower end of each tube is a ring 40^a in which is formed an eye 40^b adapted to receive a rod or lever 40. These rods may be grasped 50 from time to time and jerked sidewise a sufficient distance to turn the tubes or vibrate the same sufficiently to dislodge any ore that might have a tendency to hang back or choke the tubes. The perforations 55 formed in the pipes are preferably inclined in an upward and inward direction as shown, to prevent admission of ore, and perforations 19' are also provided at the lower ends of the retort tubes to permit ad- 60 mission of furnace gases or air for the purpose of oxidizing and increasing the temperature of the ore before it is finally permitted to discharge through the lower ends. Practically speaking, complete extraction of the 65 volatile products is in this manner possible.

A continuous operation is furthermore permitted and the furnace may be operated as a whole, without the attention of skilled furnace-men or without subjecting said men to the danger of becoming salivated. The 70 provision of the grate bar shaped frames and the coöperating cover section 6 permits the individual tubes to be readily removed when desired, the openings in the grate bar frames being sufficiently large to extract the tubes even in cases where they are considerably twisted or warped by the effect of the furnace heat.

75 The materials and finish of the several parts of the invention may be such as the 80 judgment and experience of the manufacturer may dictate.

I wish it understood that various changes in form, proportions and minor details of construction may be resorted to within the 85 scope of the appended claims, and that I do not wish to limit myself to the specific design and construction here shown.

Having this described my invention, what I claim and desire to secure by Letters Pat- 90 ent is—

1. In an ore roasting furnace, a main heating chamber and a fire-box, a plurality of open ended retort tubes extending through the heating chamber, a perforated 95 pipe extending through each retort tube and means connecting said pipes with a condenser, means for retaining the ore in the retort tubes while being heated, and said means permitting removal of the heated ore 100 from the lower open end of the retort tubes without removing said perforated pipe.

2. In an ore roasting furnace, a main heating chamber and a fire-box, a plurality of frames, each having a plurality of rec- 105 tangular openings formed therein, a plurality of open ended retort tubes extending through the heating chamber and the rec- tangular openings formed in the frames, and a pair of inclosing plates fitting each 110 rectangular shaped opening to form a clo- sure around each tube.

3. In an ore roasting furnace, a main heating chamber and a fire-box, a plurality of frames, each having a plurality of rec- 115 tangular openings formed therein, a plurality of removably mounted open ended retort tubes extending through the heating chamber and the rectangular openings formed in the frames, a pair of inclosing plates fitting each 120 rectangular shaped opening to form a closure around each tube, a fixed perforated pipe extending through each retort tube and means connecting said pipes with a con- denser.

125 4. In an ore roasting furnace, a main heating chamber and a fire box, a plurality of open ended retort tubes extending through the heating chamber, a perforated pipe ex- 130 tends through each retort tube, means con-

necting said pipes with a condenser, an ore bin surrounding the upper open ends of the retort tubes to permit a continuous delivery of ore, and a receiving plate spaced from, and mounted below, the lower open ends of the tubes.

5. In an ore roasting furnace, a main heating chamber and a fire-box, a plurality of frames, each having a plurality of rectangular openings formed therein, a plurality of open ended retort tubes extending through the heating chamber and the rectangular openings formed in the frames, a pair of inclosing plates fitting each rectangular shaped opening to form a closure around each tube, an ore bin surrounding the upper open ends of the retort tubes to permit a continuous delivery of ore, and a receiving plate spaced from, and mounted below, the lower open ends of the tubes.
6. In an ore roasting furnace, a main heating chamber and a fire-box, a plurality of frames, each having a plurality of rectangular openings formed therein, a plurality of open ended retort tubes extending through the heating chamber and the rectangular openings formed in the frames, a pair of inclosing plates fitting each rectangular shaped opening to form a closure around each tube, a perforated pipe extending through each retort tube, means connecting said pipes with a condenser, an ore bin surrounding the upper open ends of the retort tubes to permit a continuous delivery of ore, and a receiving plate spaced from, and mounted below, the lower open ends of the tubes.
7. In an ore roasting furnace, a main heating chamber and a fire box, a plurality of open ended retort tubes extending into the heating chamber within a short distance of
10. lar openings formed therein, a plurality of open ended retort tubes extending through the heating chamber and the rectangular openings formed in the frames, a pair of inclosing plates fitting each rectangular shaped opening to form a closure around each tube, a perforated pipe extending through each retort tube, a water containing tank with which the lower ends of the pipes are connected and a condenser 45 including a suction blower connected with the tank.

the bottom thereof, a perforated pipe extending through each retort tube, a water containing tank with which the lower ends of the pipes are connected and a condenser 45 including a suction blower connected with the tank.

8. In an ore roasting furnace, a main heating chamber and a fire-box, a plurality of frames, each having a plurality of staggered rectangular openings formed therein, a plurality of removably mounted open ended retort tubes extending through the heating chamber and the rectangular openings formed in the frames, a pair of inclosing plates fitting each rectangular shaped opening to form a closure around each tube, a perforated pipe extending through each retort tube, a water containing tank with which the lower ends of the pipes are connected and fixed with relation to said tubes 55 and a condenser connected with the tank.

9. In an ore-roasting furnace, a heating chamber, a vertically disposed open-ended roasting cylinder disposed in the heating 65 chamber with the interior of the cylinder out of communication with the products of combustion in the heating chamber, the upper end of the cylinder projecting into an ore-bin and the lower end of the cylinder 70 disposed above a floor or plate and spaced therefrom, which floor or plate forms the only support for the material undergoing roasting within the cylinder.

In testimony whereof I have hereunto 75 set my hand in the presence of two subscribing witnesses.

WILLIAM W. WHITTON.
